CLAIM

The ornamental design for a container with closure, as shown and described.

DESCRIPTION

FIG. 1 is a perspective view of a container with closure, showing our new design;

FIG. 2 is a first side view thereof;

FIG. 3 is a second side view thereof;

FIG. 4 is a back view thereof;

FIG. 5 is a front view thereof;

FIG. 6 is a top view thereof; and,

FIG. 7 is a bottom view thereof.

The broken lines shown in the drawings are for the purpose of illustrating unclaimed portions of the combined container and closure and form no part of the claimed design.

1 Claim, 4 Drawing Sheets
